UNITED STATES PATENT OFFICE.

CHARLES H. RICE, OF EAST SPARTA, AND THURMAN RICE, OF CANTON, OHIO.

RESILIENT WHEEL.

1,187,552.

Specification of Letters Patent. Patented June 20, 1916.

Application filed August 5, 1915. Serial No. 43,764.

To all whom it may concern:

Be it known that we, CHARLES H. RICE and THURMAN RICE, both citizens of the United States, residing at East Sparta, in 5 the county of Stark and State of Ohio, and Canton, in the county of Stark and State of Ohio, respectively, have invented a new and useful Resilient Wheel, of which the following is a specification.

10 This invention relates to resilient wheels and has more especial reference to that type of resilient wheel which is provided with a flexible rim or tire.

15 The object of our invention is to provide a wheel of the character referred to, the construction of which will reduce the jar upon a vehicle to a minimum.

20 A further object is the construction of a resilient wheel, possessing the advantages above mentioned which will be simple in construction, inexpensive to manufacture and durable and efficient in use.

25 A further object is to provide a wheel of this construction in which there will be practically no noise or rattling caused by the movement of the several parts during the operation of the wheel.

30 With these objects in view the invention consists in the novel construction and arrangement of parts, hereinafter described, illustrated in the accompanying drawings, and particularly pointed out in the appended claims, it being understood that various changes in the form, proportions, size and 35 minor details of construction may be made within the scope of the appended claim, without departing from the spirit or sacrificing any of the advantages of the invention.

40 In the drawings: Figure 1 is a side elevation of the wheel with parts broken away for purpose of illustration. Fig. 2 is a transverse sectional view on an enlarged scale showing one of the cushioning devices. 45 Figs. 3 and 4 are detail perspective views of one of the adjusting plates and rocking members of the cushioning mechanism. Fig. 5 is a fragmentary sectional view of one of the adjusting plates and a portion of an adjusting screw.

50 Similar numerals of reference indicate corresponding parts throughout the several figures of the drawings.

55 Referring more especially to the construction illustrated in the accompanying drawings, the spokes 1 are connected to the hub

2 in the usual manner a felly 3 being provided around the spokes. The annular casing 4, the form of which is best illustrated in Fig. 2, is located around the felly and connected thereto by means of the series of bolts 5 which pass through said casing and through enlarged apertures 6 located in the spaced lugs 7 provided around the periphery of the felly. Interposed between the 65 inner edge of the casing 4 and each side face of the felly is an annular gasket 8, of fibrous material, provided for the purpose of preventing any rattling of the casing. A mud guard composed of spring members 9, covered upon each side with a strip of rubber or similar material 10 is connected to the felly by nails 11 or their equivalents and located against the outer faces of the casing for the purpose of preventing dust or mud 75 from entering between said casing and the felly.

The adjusting plates 12 are provided with sockets 13 arranged to receive the rounded extremities of the adjusting screws 14, said screws passing through suitable screw threaded apertures 15 in the tire 3^a and provided with jam nuts 16 located against the inner face of the felly. Each of the adjusting plates 12 is provided with a central aperture 17 and with radially disposed V-shaped notches 18 diametrically opposite to each other and extending from the outer edges of the adjusting plate to said central aperture.

80 The rocking members 19 are of substantially annular form and are provided with the internal annular shoulders 20. Each of the rocking members 19 is provided upon its lower face with a pair of diametrically opposite V-shaped teeth 21 arranged to be located in the V-shaped notches 18 upon the accompanying adjusting plate.

85 Located around the periphery of the casing 4, within the annular depression 22 and in radial alinement with the centers of the adjusting plates 12 is a series of screws 23 the heads of said screws being counter-sunk within the outer face of the casing, jam nuts 24 being provided upon said screws and located against the inner surface of the casing. 90 The rounded extremities of the screws 23 are received within sockets 25 centrally located within the disks 26, each of said disks being provided with a concentric socket 27 in its 95 opposite face for the purpose of receiving one extremity of the cylindrical resilient

member 28, said resilient member being preferably composed of soft rubber. The lower extremity of said resilient member is located through the annular rocking member 19 and through the central aperture 17 of the adjusting plate 12, resting upon the felly. A coil spring 29 is located around the resilient member 28 and interposed between the shoulder 20 of the rocking member and the disk 26.

For the purpose of adding further resiliency or quality to the wheel, a tire 30 preferably of circular cross section and composed of soft rubber or similar material is located in the annular depression 22 which is provided around the periphery of the casing.

With the construction above described, the coil springs 29 cushion the wheel while the resilient members 28 prevent excessive compression of said coil springs thus adding a further cushioning effect to the wheel. Owing to the construction by which the rim or casing is connected to the felly only by means of the bolts 5 which pass through the enlarged apertures 6 in the lugs carried upon the felly, said bolts are free to move in any direction in said apertures, thus allowing a slight rocking motion of the cushion members when the wheel is suddenly started or stopped, said cushion members rocking between the pivotal points 23 and the V-shaped teeth 21.

The adjusting screws not only provide means by which the springs may be adjusted to center the rim or casing with relation to the axis of the wheel but they also enable the tension of the spring to be adjusted according to the weight desired to be imposed upon the wheel.

For the purpose of convenience the casing 4 is made of a plurality of sections riveted or otherwise attached together as illustrated in Fig. 1 of the drawings. By the construction of cushion members disclosed herein each cushion member comprises a double pivoted spring, pivotally connected to the felly and to the casing at its opposite extremities. As best shown in Fig. 2 each re-

silient member 28 is retained at its lower extremity within the central aperture of the accompanying adjusting plate, the upper extremity of said resilient member being spaced away from the disk 26 and arranged to be received within the socket 27 of said disk when the accompanying spring 29 is put under pressure, thus relieving the spring of a part of the weight or strain and at the same time producing the desired cushion effect. The bolts 5 will come into action where there is any difficulty in starting the wheel, contacting with the walls of the apertures 6 and causing the tire or casing to move circumferentially with the felly.

We claim:

In a vehicle wheel comprising a felly and an annular casing surrounding said felly, a set of cushioning devices spaced radially around the wheel and located between the felly and the casing, an adjusting plate provided with a central aperture laterally disposed V-shaped grooves in the upper face of said plate and sockets in the lower face of said plate, adjusting screws located through screw threaded apertures in said felly, the extremities of said screws being received within the sockets within said adjusting plate, an annular rocking member provided with an internal annular shoulder, V-shaped teeth provided upon the lower face of said rocking member and located within the V-shaped grooves within said adjusting plate, a cylindrical resilient member located through the aperture in said plate and resting upon the felly, a disk provided with a socket, said socket receiving the upper end of said resilient member, said disk provided in its upper face with a rounded socket, a pin attached to the inner face of said casing, the extremity of said pin located in the rounded socket of said disk and a coil spring interposed between said rocking member and said disk.

In testimony that we claim the above, we have hereunto subscribed our names.

CHARLES H. RICE.
THURMAN RICE.
